203,683

SAFETY PIN HOLDER ANIMAL FIGURE

Pearl Wallace, 410 1/4 S. Coronado St.,
Los Angeles, Calif.

Filed July 1, 1964, Ser. No. 80,655

Term of patent 3 1/2 years

(Cl. D34—2)

FIG. 3

The broken line showing of pins is for illustrative purposes only.

I claim:

The ornamental design for a safety pin holder animal figure, as shown and described.
